UNITED STATES PATENT OFFICE.

JOHN OLSEN, OF LYLE, MINNESOTA.

METAL CULVERT.

1,010,450.

Specification of Letters Patent.

Patented Dec. 5, 1911.

Application filed July 24, 1911. Serial No. 640,072.

To all whom it may concern:

Be it known that I, JOHN OLSEN, a citizen of the United States, residing at Lyle, in the county of Mower and State of Minnesota, have invented certain new and useful Improvements in Metal Culverts, of which the following is a specification.

The present invention relates to corrugated sheet metal pipe, adapted particularly 10 for use as a culvert.

The objects of the invention are to provide a knockdown metal culvert which can be transported to the place where it is to be used and there set up by unskilled labor; to 15 provide a culvert which is strong and rigid, and wherein the longitudinal seams or joints are of special construction to give great rigidity and resistance to displacement; to provide special means for drawing the several 20 sections of the culvert into position with respect to one another and for holding them in tight engagement.

The details of my invention will be better understood by reference to the following description taken in connection with the accompanying drawing in which—

Figure 1 is a side elevation of a portion of a culvert, Fig. 2 is a sectional elevation of the same, and Fig. 3 is a fragmentary 30 perspective view showing details of a longitudinal joint or seam.

In the construction shown, the culvert comprises a plurality of sections of which only three appear in the drawing, these being designated by the numerals 1, 2 and 3. Section 1 may be identified as a bottom section and sections 2 and 3 as top sections. The two top sections have their ends abutting against one another with the joint offset 40 set with respect to similar joints between adjacent bottom sections.

Each of the culvert sections is provided with circumferential corrugations, which give strength to the culvert and which are an important factor in the longitudinal seam or joint hereinafter described more in detail. Each of the sections is semi-circular in outline, but is somewhat larger than a semi-circle, thereby providing sufficient material for a wide overlap at the edges.

Along the edges of the lower corrugation, each convex portion 4 is cut or slit so that there is produced a plurality of integral lugs, or fingers. Every alternate finger 5 is allowed to remain in its initial position, but each of the others is bent inward at its base

to form a shoulder 6 upon which an edge of the upper section may rest. The bent fingers have curved surfaces which fit in the corrugations of the upper section and by their tight engagement with the inner surfaces thereof, serve to stiffen the structure and reinforce the joint. This gives great rigidity to the culvert and protects the sections from lateral displacement.

As a means for drawing the sections together and for holding them tightly in engagement with one another, the sections are provided along their edges with brackets 7 equipped with tightening bolts 8. These brackets are riveted to the culvert sections and are so short that the tightening bolts may be applied very close to the overlapping edges of the conduit. This obviates any tendency toward buckling or crushing, which might arise if the tightening were effected by bands which completely enveloped the pipe. Each bracket is seated in the hollow of a corrugation, and the tightening bolts project only slightly at the side 80 of the pipe.

Having described my invention, what I claim as new and desire to secure by Letters Patent of the United States is;

1. A metal culvert pipe comprising upper and lower sections, each of which is provided with circumferential corrugations, said upper section having straight edges and said lower section having its edges cut to form a plurality of fingers, some of which are bent inward to form shoulders on which said upper section may rest, each of said bent fingers having an upstanding portion arranged for tight engagement with the inner surface of the upper section, short 90 brackets secured to said sections near their edges and means for joining the brackets together to force the edges of the upper section into secure engagement with the fingers of the lower section.

2. A metal culvert pipe comprising upper and lower sections, each of which is of circular outline and somewhat greater than a semicircle and each of which is provided with circumferential corrugations, said upper section having straight edges, brackets secured to said upper section, said brackets being seated in the hollows of said corrugations, a lower section having both edges slit to form a plurality of fingers every alternate one of which is adapted to engage the outer surface of said upper section, the re-

mainder of said fingers being bent inward to form shoulders whereon the upper section may rest, said bent fingers having outstanding portions which engage with the inner surface of the upper section and strengthen the same, and means carried by said lower section and engaging with said brackets to hold said sections in place.

3. A metal culvert consisting of upper and lower sections which overlap, said sections being each provided with circumferential corrugations, said lower section having along each edge a plurality of slits dividing said edges into a plurality of integral fingers 15 of which each alternate finger is bent in-

ward to provide a shoulder on which an edge of the upper section may rest, said fingers embracing and strengthening the adjacent edges of the upper section, and brackets secured to said sections near their edges and provided with tightening bolts whereby said sections may be drawn together and held in tight contact. 20

In witness whereof, I hereunto subscribe my name this fifteenth day of July A. D. 25 1911.

JOHN OLSEN.
